UNITED STATES PATENT OFFICE.

GEORGE HEGEMAN HART, OF WEST HARTFORD, CONNECTICUT.

ELECTRIC SWITCH.

Application filed March 8, 1923. Serial No. 623,630.

To all whom it may concern:

Be it known that I, GEORGE H. HART, a citizen of the United States, and a resident of West Hartford, county of Hartford, 5 State of Connecticut, have invented certain new and useful Improvements in an Electric Switch, of which the following is a specification.

This invention relates to electric circuit 10 making and breaking devices, and, more particularly, to snap switches.

One object of the invention is to provide an improved construction and arrangement of parts by which is produced an efficient, 15 durable, inexpensive and compact electrical switch.

Another object is to provide an efficient and compact switch which is adapted to open and close a number of circuits at very nearly 20 the same time without destructive arcing.

The invention, accordingly, consists in the features of construction, combinations of elements and arrangement of parts which will be exemplified in the construction hereinafter set forth and the scope of the application of which will be indicated in the appended claims.

In the drawings which illustrate a practical embodiment of my invention and in 30 which similar reference characters refer to similar parts,

Fig. 1 is a plan view of the switch, portions being broken away to more clearly show the arrangement of contacts;

Fig. 2 is a view, partly in section, showing the manner of cooperation of the switch contacts; and

Fig. 3 is a perspective of one of the switch contacts showing the lug provided as a 40 mounting therefor.

Referring to the drawing, and more particularly to Fig. 1, the switch comprises a base 1 of porcelain or other suitable insulating material, upon which is mounted the 45 switch mechanism including stationary contacts 2, a rotary contact or blade 3, and a third or supplemental contact 4. Such a switch as is here illustrated is more particularly adapted for use in apparatus as, for 50 instance, an electric stove wherein there is provided a heating element such as is indicated diagrammatically at 5 and a pilot light 6 which is employed for the purpose of indicating that the current is turned on. The 55 switch is operated through a control handle 7 which may have a plurality of positions

and may, if desired, be adapted to turn in either direction, causing the movable blade, such as 3, to snap into and out of engagement with the stationary contacts, such as 60 the one indicated at 2. It is usual to provide the heating unit or units, such as that shown at 5, in such manner as to obtain different heats. In the present embodiment, two of the terminals 8 are shown connected to opposite ends of the heating unit 5, and the third terminal is connected to the midpoint thereof. In order to vary the heat given off by this unit, the switch is adapted to connect the two sections of the heating unit in 65 multiple, series, or singly when the high, low, or medium temperatures, respectively, are desired. There may also be provided a fuse, such as is shown in the plug fuse 9, associated with one of the current bus bars 70 10. The lamp 6 is, in the present embodiment, shown adapted to be connected in parallel with the current source whenever the switch is in a circuit making position, and its circuit, which includes the binding post 75 11 and the switch contact 4, is completed whenever the switch is in one of its "on" positions.

The switch contact 4 is mounted by means of a suitable screw or rivet 12 upon a lug 80 13 which is rigidly mounted on the base 1 by a screw 14 extending from the bottom of the base through the lug. A suitable threaded aperture 15 is also provided to accommodate the binding post 11. The contact 4 is so disposed as to extend between the pair of stationary spring arms of which each of the stationary contact members 2 is composed. Between the contact 4 and the spring arms there is inserted suitable insulating material which may be in the form of sheets 16 to prevent any arcing between the contact 4 and the contacts 2. For the same purpose, the spring contact 4 is positioned somewhat from the contact faces of 90 95 100 the spring arms. The movable blade 3 is adapted to pass between the pair of stationary spring arms and to be engaged thereby on its opposite sides. When in such position, it contacts at its extreme end edge 105 with the contact 4, thus, at the same time, completing the circuit of the heating element 5 and the lamp 6.

Heretofore, in switches of this type which employed an auxiliary lamp contact for the 110 purpose above described, it has been proposed to mount such contact alongside the

main contact and to widen the movable contact or blade so as to be engaged simultaneously by both of the stationary contacts. When the switch is comparatively small, the 5 width of the blade is such that in passing from one stationary contact to the other an arc may be produced between the two successive stationary contacts and the blade which eventually burns and destroys the 10 switch. It is noted that the auxiliary spring contact 4 in the present embodiment is so positioned with respect to the center about which the movable blade 3 rotates that its contacting face lies within the angular 15 limits included between the side edges of the stationary contacts 2. In this construction, it is not necessary that the blade 3 be of unusual width in order to contact with both the lamp contact and the main contact 20 simultaneously, and the difficulty above mentioned is thereby avoided while at the same time the compactness of the switch is retained.

Thus, by the above described construction, 25 are accomplished, among others, the objects hereinbefore referred to.

As many changes could be made in the above construction and many apparently widely different embodiments of this invention 30 could be made without departing from the scope thereof, it is intended that all

matter contained in the above description or shown in the accompanying drawings shall be interpreted as illustrative and not in a limiting sense.

35

It is also to be understood that the language used in the following claims is intended to cover all of the generic and specific features of the invention herein described, and all statements of the scope of 40 the invention which, as a matter of language, might be said to fall therebetween.

I claim as my invention:

1. In an electrical switch, a contact member having a pair of opposed contact faces, 45 a switch blade arranged to be engaged between said faces, and a contact disposed between the side edges of said faces and insulated therefrom and arranged to contact with said blade when the latter is engaged 50 by said pair of faces.

2. In an electrical switch, a contact member having a pair of opposed spring arms, a movable contact member arranged to be engaged on its side faces between said arms, and a spring contact disposed between said 55 pair of stationary arms and insulated therefrom and arranged to contact with the end of said movable contact when the latter is engaged by said arms.

GEORGE HEGEMAN HART.
